STRIP OR RIBBON MAKING METHOD AND APPARATUS

Francis J. Rippl, Cleveland, and Elmer B. Isaac, Cleveland Heights, Ohio, assignors to General Electric Company, a corporation of New York

Application March 13, 1941, Serial No. 383,096

5 Claims. (Cl. 164—68)

Our invention relates to a method of providing the combustible filling material for flash lamps, and more particularly to a method and apparatus for cutting uniform strips or ribbons from a thin sheet of the combustible material to produce such filling material. A flash lamp containing such material is disclosed in our application Serial No. 322,520, filed March 6, 1940. This application is a continuation-in-part of our application Serial No. 353,650, filed August 22, 1940, now Patent No. 2,297,368, dated September 29, 1942.

Prior to our invention, the only commercially successful flash lamps contained a combustion supporting gas and a very loosely distributed metal foil or wire which, upon ignition, burned extremely rapidly to produce an intense flash of light. The speed with which the burning takes place makes it possible to receive the full benefit of the light photographically. However, the light flash must occur within a very definite interval after the lamp is set off, in order that the photographic apparatus may be properly synchronized therewith. Heretofore, the desired rate of burning could be obtained only by the use of extremely thin metal foils or fine wires as the combustible materials. However, the manufacture of such materials is relatively costly and difficult. The interval or lag between the moment the flash lamp is set off and the moment it reaches a usable brightness is also somewhat difficult to control when such materials are used, and it necessitates costly procedures and tests during the manufacture of the flash lamp to maintain uniformity of the said interval.

One object of our invention is to provide a more economical method and apparatus for supplying the combustible filling material for flash lamps. According to our invention, narrow strips or ribbons of a combustible material are formed by repeated cutting or trimming operations on a thin sheet thereof which is readily and economically procurable, and a number of such strips or ribbons are introduced into the bulb of the flash lamp in a manner causing them to be distributed uniformly about the interior thereof. The apparatus for forming the strips or ribbons comprises means for feeding the sheet of combustible material at a very definitely established rate, and means for cutting extremely narrow strips or ribbons from said sheet in accordance with the feeding motion. Means are also preferably provided for separating certain numbers of said strips or ribbons and for effecting the removal

of the separate strips or ribbons from the cutting apparatus.

Another object of our invention is to provide apparatus for automatically feeding the sheet of combustible material in a very precise manner so that strips or ribbons of very definite width are separated therefrom by the cutting apparatus. The feeding operation is very difficult to accomplish satisfactorily in that the sheet is of the order of .001 inch in thickness and usually of considerable length so that it must be kept as a roll. The strength of the sheet, which is preferably of aluminum, magnesium or an alloy thereof, is therefore relatively slight and it could be readily bent or stretched out of shape so that the feeding and cutting operations would be improperly performed. The metal sheet also presents a smooth surface which is difficult to grip and feed properly.

Another object of our invention is to provide apparatus for cutting extremely narrow and uniformly shaped strips or ribbons from the metal sheet in a very precise and rapid manner. Ordinary cutting apparatus is not satisfactory for this purpose, since it tends to tear the sheet into strips because of the thinness thereof and does not produce strips of sufficient uniformity. Torn or non-uniform strips do not have a definite size and, therefore, impart indefinite or uncontrollable characteristics to the flash lamp. Ordinary cutting apparatus can not produce strips with sufficient rapidity to permit said strips to replace present foil and wire fillings in flash lamps and it often becomes entirely inoperative after short periods of use.

Other objects and advantages of our invention will appear from the following detailed description of a species thereof and from the accompanying drawings.

Our present application is a continuation-in-part of our application Serial No. 353,650, filed August 22, 1940.

In the drawings, Fig. 1 is a plan view of apparatus comprising our invention; Fig. 2 is a vertical section through said apparatus taken along line 2—2 of Fig. 1; Fig. 3 is a perspective view, on a larger scale, of a section through the principal parts of said apparatus taken along line 3—3 of Fig. 1; Fig. 4 is a vertical section through adjacent peripheral portions of feed rolls in engagement with the metal sheet, on a still larger scale; Figs. 5 and 6 are side elevations of gear trains for the feeding means and the discharge means respectively; Fig. 7 is a vertical section through one-half of a modification of

the cutter; Fig. 8 is a side elevation of one end portion of the modified cutter and associated apparatus from which a section corresponding to that shown within line 8—8 of Fig. 7 has been removed; Fig. 9 is a plan view of a second embodiment of apparatus comprising our invention; Fig. 10 is a vertical section through said embodiment taken along line 10—10 of Fig. 9; Fig. 11 is a vertical section through the cutting and feeding means thereof; Fig. 12 is a vertical section through a bearing for the cutter along line 12—12 of Fig. 9; Fig. 13 is a side elevation of the cutting means; and Fig. 14 is a side elevation of the gear train for the feeding means for the above embodiment.

The combustible material is, in the instance shown in the drawings, in the form of a sheet 10 of aluminum .001 inch in thickness, which is of uniform width and of such length that it is wound onto the roll 11. Such material, while it is extremely thin, is insufficiently thin to be effectively ignitable when comparatively wide strips are used as the filling material for flash lamps, but the material is effectively ignitable when cut into extremely narrow strips. The free end of the sheet 10 extends between the rolls 12 and 13 of the feeding means which automatically advances it over the upper surface of the stationary knife edge 14 and into the path of movement of cutting edges 15 of the rotating cutter 16. A moving belt 17 carries the strips or ribbons 18 from the cutting means as rapidly as they are formed.

The rolled combustible material 11 is held by the conical plugs 19 which are forced into opposite ends of a central opening therein and is supported by the rod 20 which is held by the arms 21 extending from the frame 22. The ends of the rod 20 are located in open slots in the arms 21 and are engaged by the fingers 23 thereon which prevent lateral movement of said rod 20. This construction permits the roll 11 to be quickly replaced and does not allow the sheet 10 to shift laterally in the apparatus.

The metal sheet 10 is drawn from the roll 11 by the rotative motion of the feeding means which is provided primarily to advance said sheet 10 to the cutting means. The feeding means is comprised of the feeding rolls 12 and 13 which are located relatively near the stationary knife edge 14, and is directly responsible for the width of the strip 18 cut from the sheet 10 since it feeds said sheet 10 over said knife edge 14 and into the path of the cutting edges 15 of the cutter 16. In this instance only .000685 of an inch of movement is required of the sheet 10 between each cutting action since each of the strips or ribbons 18 is to be of this width and the feed rolls 12 and 13 are turned at a uniform rate producing this movement with no apparent disturbance in said cutting action. The feed roll 12 is mounted in bearings in the uprights 24 at opposite sides of the bed 25 for the knife edge 14 whereas the feed roll 13 is mounted in floating bearing blocks 26 within slots in said uprights 24. Springs 27, which are located between the top of the bearing blocks 26 and the collars on the lower end of the adjusting screws 28, cause the rolls 12 and 13 to engage the sheet 10 with the necessary pressure. The screws 28, in turn, are mounted on the bars 29 over the slotted ends of the uprights 24.

The metal sheet 10 must be fed in a very positive manner in order that uniformly wide strips or ribbons 18 will be cut therefrom and accord-

ingly must be especially constructed so that the smooth surface of said sheet 10 can be gripped and held thereby. It is preferred that the peripheries of the feed rolls 12 and 13 have matching protuberances and depressions therein, which in this instance have a modified screw thread form in that it permits the sheet 10 to be bent during engagement with the feed rolls 12 and 13 which assures positive contact and gripping action across the full width thereof. The feed rolls 12 and 13 are arranged so that the ridges 30 of the threads in one roll are over the grooves 31 of the threads of the second roll in the manner shown in Fig. 4 and the pressure of engagement of said rolls 12 and 13 is such that the sheet 10 is bent to the form shown. Any irregularity in the rolls 12 and 13 is therefore of no consequence.

The metal sheet 10 does not return to its original form after leaving the feed rolls 12 and 13 and, in its present corrugated form, is so stiff that it is fed to the cutting means without difficulty. In the instance shown, the metal sheet 10 has an effective thickness of .003 of an inch, whereas the plane sheet 10 is but .001 of an inch in thickness.

The feeding operation advances the end of the metal sheet 10 over the stationary knife edge 14 and into the path of movement of the edges 15 of the cutter 16 which rotates at a uniform rate of speed in a clock-wise direction. A bar 32 mounted directly over the stationary knife edge 14 engages the upper surface of the sheet 10 at this point and keeps it from shifting about. Both the cutter 16 and the bar 32 are mounted on the bearing blocks 33 at opposite ends thereof, the latter indirectly through the arms 34, and are retained at a fixed position on the frame 22, whereas the knife bed 25 can be adjusted with relation thereto by manual rotation of a plurality of screws 36 located along the back thereof. The twelve edges 15 of the cutter 16 and the bearings in the blocks 33 are manufactured with extreme accuracy so that the cutting action in every instance is exactly alike and the strips or ribbons 18 drop free of both the stationary knife edge 14 and the edges 15 of the cutter 16. The edges 15 of the cutter 16 are diagonally arranged thereon in the instance shown. The strips or ribbons 18 severed from the metal sheet 10 fall onto separate areas of the moving conveyor belt 17, and do not have the corrugated form of said sheet 10 but have an irregular appearance which is believed largely due to a non-uniform twisted condition. The conveyor belt 17 carries the strips or ribbons 18 either to means for storing them in some manner or to manually or mechanically operated means for inserting them into the bulbs of flash lamps.

The cutter 16, the feed rolls 12 and 13 and the belt 17 are the only driven members of the machine and are actuated from a common source, preferably an electric motor (not shown) which engages the cutter 16 through the belt 35, the pulley 36 and the coupling 37. The shaft 38 on which the pulley 36 is mounted extends from one side of speed reducer 39 which, in combination with the train 40 of gears shown in Figs. 1 and 5, provides for the operation of the feed rolls 12 and 13. The particular feeding motion desired in this instance is developed through a speed reduction of 286 to 1 which is divided into a 50 to 1 reduction in the speed reducer 39 and a 5.72 to 1 reduction in the gear train 40. The gear train 40 is driven through the shaft 41 of 70 the speed reducer 39 which provides the support

for the gear 42 and comprises gears 42, 43, 44, 45 and 46, the latter of which is connected to the feed roll 13 through the shaft 47 and coupling 48. The intermediate sets of gears 43 and 44—45 are mounted on the arms 49 which are adjustably attached to the frame 22 of the apparatus so that other gears of different sizes may be substituted for those in said train and the width of strips or ribbons 18 cut can be changed at will. Gear 42 is not provided with teeth completely around its periphery but has three groups thereof which have sufficient length to cause the feeding means to operate for definite periods during which a sufficient number of strips or ribbons 18 are formed to supply one flash lamp. When one of the groups of teeth are not engaged with gear 43, the feeding means is not operated and an interval occurs during which no strips or ribbons 18 are cut. The conveyor belt 17, however, continues to move during these intervals and a space such as shown in Fig. 1 occurs between the strips or ribbons 18 for one flash lamp and those for another. The lengths of the operating and rest periods are, of course, established in accordance with the requirements of the flash lamps and on different occasions when a greater or lesser number of strips or ribbons 18 are required, changes can be made in the gear train 40 to produce the desired results. In some instances the counting feature of the apparatus may not be desired and a gear having teeth over its full periphery may be substituted for gear 42. The conveyor belt 17 is preferably moved at a rate of speed which causes the strips or ribbons 18 to be spaced from each other in the manner shown and is actuated from the drive shaft 38 of the speed reducer 39 through the gear train 50 shown in Figs. 1 and 6, the shaft 51 and the roll 52. The shaft 38 supports the gear 53 of the gear train 50 and the motion imparted to it is transferred through the gears 54, 55, 56 and 57 in order to the gear 58 on the shaft 51. Support for the shaft 51 is provided by portions (not shown) of the frame 22, whereas support for the pins 59 and 60 on which the gears 54—55 and 56—57 respectively are mounted is provided by the bar 61 which is attached to the frame 22.

The metal strips or ribbons 18 can be transferred directly to the flash lamps from the conveyor belt 17 but each group thereof must be rumpled during said operation in a manner causing them to be uniformly distributed about the interior of the lamp. A short stick or lead pencil in the hand of an operator can be used to pick up the strips or ribbons 18 and, if agitated back and forth, causes them to be formed into a loosely formed wad or ball which is then inserted into the lamp. The strips or ribbons 18 are sufficiently stiff and irregular in form (although of uniform section) to quickly form the wad or ball desired and, after insertion in the lamp, are sufficiently stiff to retain their portion in said lamp. Sudden jarring or rough handling of the lamp does not cause the strips or ribbons to shift materially.

The speed of operation of the cutting apparatus is such that a sufficient number of strips or ribbons 18 for a single lamp can be made in from 2 to 3 seconds, which is more rapidly than they can be inserted in flash lamps manually. Mechanical means must then be used to take the strips 18 from the conveyor belt 17. Such mechanical means may provide means for storing the strips 18 and may comprise a supply reel in

place of roll 52, a continuous sheet of paper or the like in place of the belt 17, and a driven collecting reel. The collecting reel may be arranged so that the paper is wound upon it before the strips 18 can move from position and may be constructed so as to be readily removed to some other location where the paper may be unwound and the strips released as needed.

The modified apparatus shown in Figs. 7 and 8 comprises a rotary cutter 16' constructed so that the cutting edges 18' represented by the knives 62 are removable. Means are also provided in said cutter 16' for separating the strips or ribbons 18 from the knives 62 since said strips or ribbons 18 tend to adhere thereto under certain conditions of operation. Each knife 62, of which there are eight in the instance shown, rests in a groove in the cutter 16' which definitely positions it, each knife being held in place by block 63 which is attached to the cutter 16' by the screws 64. Under certain conditions of operation the weight of the strips or ribbons 18 would not be sufficient to cause them to drop from the cutter 16', but a relatively weak or low pressure jet of air is caused to be blown along the faces of the knives 62 and the blocks 63 to separate said strips or ribbons therefrom. The air emerges from a larger opening 65 between the innermost edges of said faces into which it is conducted from a central opening 66 in the cutter 16' through regularly spaced radial passages 67 therein and is conducted to the cutter 16' from a supply source (not shown) through the flexible pipe 68 and the pipe 69 which is held by a portion 70' of the frame 22 and which engages the end of the cutter 16', the terminus of the opening 66. The opposite end of the opening is plugged.

The embodiment of our invention shown in Figs. 9 and 10 includes still further modifications thereof which contribute to the ease of manufacture and repair, as well as a more satisfactory operation of the apparatus. In this present embodiment, the sheet 10 of the combustible material is drawn from a roll 11 (at the right in Figs. 9 and 10) by the normal operations of the feeding means 70 (near the center of said figures) and passes from the roll 11 to lubricating means 71 and then to the feeding means 70 in the course of its movement. The cutting means 72 receives the portion of the sheet 10 advanced beyond the feeding means 70.

The roll 11 is carried by the conical faces of two plugs 19 which are forced into the opposite ends of a central opening therein, and is supported by the rod 20 and two upstanding arms 21' extending from the frame 22' of the apparatus. The ends of the rod 20 rest in open slots in the upper ends of the arms 21' and can be readily removed from the apparatus when the roll 11 is to be replaced.

The lubricating means 71 is the next portion of our apparatus engaged by the sheet 10 and is provided to apply a very thin coating to both surfaces of said sheet 10 which will prevent the occasional tendency of the strips 18, severed from said sheet 10, to adhere to the cutting means 72. Since the sheet 10 is made of aluminum, in this instance, it is preferred that the lubricant be a one to two tenths per cent solution of stearic acid and alcohol, the alcohol functioning as the carrier and being evaporated from the sheet 10 soon after it leaves the lubricating means 71. The lubricant is contained in the tank 73 of said means and is transferred to the sheet 10 in the course of its movement which carries it through a slot

between one rim of the tank 73 and the cover plate 74, down into the lubricant and then out a second corresponding slot over the opposite rim of said tank 73. Guide rolls 75 and 76 adjacent said rims keep the sheet 10 from touching the tank 73, whereas a larger roll 77 rides on the intermediate portion thereof and pulls it down into the lubricant. The ends of the rolls 75, 76, and 77 are located in slots in the tank 73 which permit the rolls to be lifted therefrom after the cover plate 74 is removed so that they and said tank 73 can be cleaned.

The next portion of the apparatus engaged by the sheet 10 is the feeding means 70 which is a modification of our previously described apparatus in that different feed rolls 12' and 13' (Figs. 9, 10, and 11) are provided. In this particular instance the lower feed roll 12' is made of steel and has a smooth surface, whereas the upper feed roll 13' has a metal core 78 and resilient rubber outer covering 79 presenting only a comparatively smooth surface. The ends of the lower feed roll 12' are journaled in the uprights 24 attached to opposite ends of the bed 25' which rests on the block 80 carried by the frame 22' and, being positively mounted, cause said roll 12' to be a fixed member against which the sheet 10 is pressed by the upper roller 13' which is journaled in floating bearing blocks 26 within slots in said uprights 24. The lower roll 12' is the only driven member of the feeding means, in this particular instance, and is caused to advance the sheet 10 only in that said sheet 10 is pressed against it with sufficient force to prevent any slipping. The downward pressure of the upper roll 13' is developed from the expansion force of the springs 27 located between the top of the floating blocks 26 and the adjusting screws 28 carried by the bars 29 on the upper ends of the uprights 24 and is sufficient to cause the upper roll 13' to be deformed slightly so that very slight variations in the sheet 10, etc., have no effect on the feeding operation. The rubber covering 79 on the upper roll 13' is made by pressing a slightly smaller rubber tube of about 40 durometer resiliency over the metal core 78 thereof and then grinding said tube to uniform size from end to end so that it runs true and has uniform characteristics. The resiliency of the upper roll 13' can not distort the sheet 10 since the lower roll 12' is smooth and rigid and can not disturb the very exact feeding schedule in that said schedule depends on the very definite periphery of the lower roll 12' since the upper roll 13' idles.

The portion of the sheet 10 advanced beyond the feeding means 70 passes directly to the cutting means 72 which provides a stationary knife edge 14' on a knife 81 attached to the bed 25' and a specially formed cutter 16'' having eighteen cutting edges 15''. The construction of these parts allows them to be shaped satisfactorily since the knife 81 can now be separated from the bed 25' and handled conveniently and the cutting edges 15'' of the rotatable cutter 16'' can now be treated and lapped by certain very desirable methods and apparatus. The knife 81 is attached to the bed 25' by screws 82 along its length, whereas the bed 25', in turn, is securely clamped to the block 80 by the bolts 83 and maintains its very critical relation to the cutter 16'' since the bearing blocks 33' in which the ends of said cutter 16'' are journaled are also fastened to said block 80.

The satisfactory operation of the cutting means 72 depends both on the condition of the cutting

edges 14' and 15'' of the knife 81 and the cutter 16'' respectively, and on the relation of these parts to each other. If either of these conditions is improper, the strips 18 are very apt to be torn from the sheet 10 and to be of unequal width, and may develop a tendency to adhere to one or the other of the cutting edges 14' or 15''. Torn or unequal width strips destroy the properties of the flash lamps in which they are used, whereas an adhering strip 18 keeps one or more strips from the flash lamps and is very likely to block up the apparatus so as to destroy the normal movement of all the strips 18. The sharpening operation is comparatively simple in regard to the knife 81, since both faces thereof forming the cutting edge 14' are straight and can be lapped against a flat surface. The cutter 16'', on the other hand, is round and has a prescribed lead to the cutting edges 15'' thereof which causes it to be more difficult to sharpen. The land or face adjacent each cutting edge 15'' which is on the periphery of the cutter 16'' can of course be sharpened while said cutter 16'' is being rotated, but the adjoining substantially radially extending face of said cutting edge must be treated in some other manner. One particularly novel feature of the cutter 16'' is that each radially extending face of said cutter 16'' forms a longitudinally extending semi-circular groove so that a round lapping tool of slightly less curvature than said face can be run back and forth along said face while being rotated to condition the edge.

The relative position of the knife 81 and the cutter 16'' are adjusted by altering the position of the bed 25' on the block 80 by adjusting the screws 84 extending from the plate 85 at the back thereof and the screws 86 extending from a plurality of fingers 87 at the forward edge thereof. The plate 85 is attached to the frame 22' of the apparatus by means of the bars 88 and 89 and retains its position in regard to the block 80 since said block 80 is fastened to the frame 22' by the bolts 80 (Fig. 9). Once the knife 81 is brought to the correct position there is positive assurance that it will remain in this position. The cutter 16'' is a rotatable member, however, and is more difficult to hold in place with the needed accuracy since the working clearance in the bearings at the ends thereof must be so small that said cutter can not shift about even within extremely narrow limits. It is preferred, therefore, that each end of the cutter 16'' as shown in detail in Fig. 12 be held between three similarly shaped shoes 91 which are mounted on the ends of screws 92 threaded in the bearing blocks 33' in that said shoes 91 can be adjusted until the working clearance therebetween is reduced to the very minimum and so that a lubricant can be effectively introduced therebetween. The lubricant is fed to the bearing by a felt wick 93 which is fastened to an end of one of the shoes 91 by a strap 94 and which extends into a well 95 in the bearing block 33'. A flat ring 96 (Fig. 9) is fastened to the bearing block 33' to seal the lubricant in the chamber containing the shoes 91 whereas a felt washer 97 is attached to the opposite face thereof to prevent any seepage of lubricant from about the end of the cutter 16'' from being thrown onto the sheet 10.

An important part of the cutting means 72 is the bar 32' (Fig. 11) which is located directly over the forward edge of the sheet 10 and the knife 81. The bar 32' contributes to the extreme accuracy with which the cutting means 72 operates

in that it functions as the means of holding the end of the sheet 10 in place over the cutting edge 14' so that said sheet 10 may not twist or curl and be cut unevenly. The bar 32' presents a smooth straight surface for its entire length and is mounted on two arms 34' extending from the bearing blocks 33' at opposite ends of the cutter 16''. Each arm 34' (Fig. 13) is pivoted on a screw 98 held by the bearing block 33' and is swung down to the limit established by the engagement of stop screw 99 and stud 100 by the spring 101. At such times the bar 32' is normally .002 to .004 inch above the sheet 10 so that no resistance is provided to the feeding movement of said sheet and the said sheet 10 is still prevented from raising from its position on the knife 81. The bar 32' is kept within .010 to .015 inch of the cutter 16'' and is in substantial alignment with the cutting edge 14' of the knife 81.

As in the prior instance, the rotatable cutter 16'' is the driven member of the apparatus and is engaged by the driving means (not shown) through the belt 102, pulley 103, and coupling 104. The coupling 104 consists of two sections having interlocked teeth separated by pieces of only comparatively rigid material and provides for a slight difference in alignment of the cutter 16'' and the shaft 105 of the speed reducer 106 on which said pulley 103 is mounted so as to prevent the driving means from disturbing the position of the cutter 16''. The sheet feeding means 70 is also driven through the speed reducer 106, but through shaft 107 thereof, and the train 40' (Figs. 9 and 14) of gears comprising gears 42', 108, 109, 110, 111 and 46', the latter of which engages the end of the feed roll 12' through shaft 47' and coupling 48'. This train 40' of gears differs from the other train 40 thereof principally in the substitution of gears 42' and 108, 109, 110 and 111 for gears 42 and 43 respectively. Gear 42' is provided since a different number of strips 18 must be supplied in each series produced by the apparatus as the flash lamps in which the filling (strips 18) is used are larger and require about 900 such strips 18. The group of teeth on the gear 42' producing this period of operation extends nearly around the periphery of the gear 42' and limits the feeding means to one rest and one operation period for every revolution of said gear 42'. The gears 108, 109, 110 and 111 permit suitable changes to be made in the gear train 40' to allow the feeding means 70 to be operated at slightly different speeds so that the width of the strips 18 can be varied. This provision is desirable in that the strips 18 for any one lamp must have very definite characteristics even though it may not be possible to provide the metal sheet 10 in exactly the same thickness at all times. Different sheets 10, as well as different sections of the same sheet 10, may vary from .0004 to .0013 inch in thickness and corresponding increases or decreases must be made in the width of strip 18 cut therefrom in order to maintain the characteristics of said strips 18 and the flash lamps in which they are used.

The adjustment of the cutting operation is made by substituting different size gears for gear 111 and is permitted in that gear 111 is mounted on a pin 112 on the free end of a movable arm 113 pivoted on the pin 114. A spring 115 which extends between posts in the arm 113 and an adjacent stationary part of the apparatus pulls said arm 113 so that the gears 46' and 111 mesh with each other at all times regardless of their size. The gear 110 is also mounted on the pin 112 and

swings about the gear 109 on pin 114 with the movements of said arm 113. Pin 114 and shaft 47' are supported by the bracket 116 and arm 117 respectively. The present gear train 40' is also better adapted to provide different width strips 18 for flash lamps requiring particular widths thereof.

It is preferred that the strips 18 be introduced into the envelope of a flash lamp and be "worked" into the combustible filling therefor directly after they are manufactured in the cutting apparatus since they are extremely light in weight and difficult to handle. Such an arrangement also allows means to be attached to cutting apparatus for separating out various numbers of said strips 18 which constitute the prescribed filling for a flash lamp. The preferred method of effecting the transfer makes use of the current of air flowing into open mouth of a nozzle 118 located below the knife 81 to pick up and connect to a source of vacuum for picking up and carrying the strips 18. A plurality of nozzles, each connected to separate and different lamp filling apparatus, can be provided on such occasions and each can be controlled through the feeding means so as to make the feeding operation entirely automatic. The method and apparatus for feeding the strips 18 in the above manner is the subject matter of United States patent application, Serial No. 374,372, filed January 14, 1941, by Geiger and Davidson and assigned to the assignee of the present invention.

What we claim as new and desire to secure by Letters Patent of the United States is:

1. Apparatus for making combustible filling material for flash lamps comprising a stationary knife edge, means for feeding an end portion of a sheet of the combustible material over the knife edge, a rotatable cutter located in operative relation to the knife edge having a plurality of cutting edges at the periphery thereof and having cylindrical end portions, bearings at each end of the cutter comprising a plurality of blocks and means capable of adjustment for holding said blocks against the cylindrical end portions of the cutter, means for rotating the cutter to cause each of said edges to engage and pass the knife edge to cut an extremely narrow strip of said sheet extending beyond said edge and means for operating the feeding means to advance succeeding strips of said sheet into the path of movement of the cutting edges.

2. Apparatus for making combustible filling material for flash lamps comprising means for cutting extremely narrow strips from an end portion of a sheet of the combustible material, a pair of feed rolls located adjacent the cutting means adapted to engage the opposite sides of the sheet having resilient and substantially rigid peripheral portions respectively to cause positive engagement between the sheet and said rolls, and means for rotating the feed roll having the substantially rigid peripheral portion and operating the cutting means in proper synchronization to each other to cause the sheet to be advanced to the cutting means and strips of the desired width to be cut therefrom.

3. Apparatus for making combustible filling material for flash lamps comprising means for cutting extremely narrow strips from an end portion of a sheet of the combustible material, a pair of metal feed rolls located adjacent the cutting means adapted to engage the opposite sides of the sheet, one roll having a rubber peripheral portion to cause positive engagement

between the sheet and said rolls, and means for rotating one of the feed rolls and operating the cutting means in proper synchronization to each other to cause the sheet to be advanced to the cutting means and strips of the desired width to be cut therefrom.

4. Apparatus for making combustible filling material for flash lamps comprising means for cutting extremely narrow strips from the end of a sheet of the combustible material, means for feeding said sheet to the cutting means at the necessary rate of speed and means for applying a lubricant to said sheet to prevent the strips from adhering to the cutting means.

5. Apparatus for making combustible filling material for flash lamps comprising means for cutting extremely narrow strips from the end of a sheet of the combustible material, a tank located adjacent said cutting means adapted to hold a lubricant, means for holding a portion of the sheet in the tank to cause it to be coated with the lubricant and means located between the first-mentioned means and the tank for drawing the sheet through said tank and feeding it to the cutting means.
